BRUSH HOLDER

Oscar F. Holmberg, Chicago, Ill.

Application June 8, 1935, Serial No. 25,539

10 Claims. (Cl. 206—15.1)

The present invention relates to holders for paint brushes and the like.

One object of the present invention is to provide a paint brush holder of an economical and efficient form which can be used for retaining paint brushes either during inactive periods while the brush is being used for painting or during the time the brush is immersed in a fluid during storage periods.

10 Another object of the present invention is to provide a holder for brushes in which a brush can be suspended without substantial contact between the frame of the holder and the bristle portion of the brush.

15 Another object of the present invention is to provide a brush holder which is adapted to securely hold a brush in fixed position whereby the bristles of the brush will be protected.

Another object of the invention is to provide 20 means for readily removing the holder from contact with the brush.

A further object of the invention is to provide a brush holder including a gripping jaw construction thereon which can be readily adjusted to 25 adapt the holder to retain brushes of varying thicknesses.

To these and other ends the invention resides in certain improvements and combinations of parts, all as will be hereinafter more fully described, 30 the novel features being pointed out in the claims at the end of the specification.

In the drawing, illustrating a preferred embodiment of the invention:

Fig. 1 is a front view of the brush holder illustrating a brush held in place therein; and

Fig. 2 is a perspective view of the brush holder.

Similar reference numerals throughout the several views indicate the same parts.

40 Referring particularly to the drawing, the brush holder comprises a frame indicated generally at 5 supporting one or more brush gripping members 6, 6.

The frame 5, as disclosed, is substantially U-shaped and, in the present instance, comprises a 45 cross member 7 connecting the upright branches or legs 8, 8 of the frame. One or both of the branches or legs 8, 8 may be advantageously mounted so as to provide for outward deflection thereof relative to the frame. For this purpose the frame is preferably formed of resilient material such as relatively heavy wire, although the frame could, if desired, be fabricated of material 50 other than wire and have a shape other than round in cross-section.

55 In order to keep the tip of the bristles substantially out of contact with the bottom of any receptacle in which the brush and holder may be placed the base portion 7 of the frame is preferably formed with downwardly projecting legs 9, 9 which, in the present instance, may be advan-

tageously formed by extending the branches 8, 8 of the frame down beyond the cross member 7 and then reversely bending the material of the frame to form relatively rigid legs of double thickness.

The gripping members 6, 6 on the branches 8, 8 are preferably formed of thin metal of a resilient character but at the same time capable of some degree of deformation so as to enable the jaws 10, 10 to be bent closer together or farther apart to adapt them to brushes of varying thicknesses. Flared portions 11, 11 are formed on the ends of the jaws 10, 10 of the gripping members to facilitate the movement of the gripping member onto the bristle base 12 of the brush.

The upright branches or legs 8, 8 of the frame 5 are preferably permanently secured to the respective gripping members 6, 6. In the present invention this is accomplished by means of soldering, but obviously the gripping members 6, 6 may be secured to the legs 8, 8 in other ways known in the art.

Finger engaging portions or elements 13, 13 are preferably associated with the gripping members so as to facilitate removal of the gripping members from the brush, when it is so desired. For this purpose the branches 8, 8 of the frame 5 are preferably extended beyond the gripping members 6, 6 so as to clear the shoulders 14, 14 of the brush. For the purpose of making these finger engaging members 13, 13 more rigid the branches 8, 8 of the frame are preferably reversely bent so that the free end thereof is disposed in contact with the gripping member. In the present instance both the main portion of the branches 8, 8 and the reversely bent portions are secured along the backs of the gripping members, although this need not necessarily be the case.

When it is desired to use the brush holder of my invention it is only necessary to press the gripping members 6, 6 onto the edges of the bristle base of the brush, and by reason of the resiliency of the gripping members 6, 6 the brush will be firmly and securely held in place. If the spacing of the jaws 10, 10 of the gripping members is too great for the thickness of the brush which it is desired to retain in the holder the jaws 10, 10 may be pressed together to a distance at which the inner surfaces of the flared portions 11, 11 are somewhat closer together than the thickness of the brush. In this way the brush may be firmly held from displacement when the gripping members 6, 6 are pressed thereon.

In some cases it is found desirable to dispense with one of the grippers 6 and employ only a single gripper.

It is to be further noted that the brush holder of my invention is adapted for brushes of varying widths. If, for example, the brush to be held in the holder is narrower than the brush disclosed in the drawing it is only necessary to bring

- the grippers 6, 6 into firm engagement with the bristle base of the brush, as previously described. The resiliency of the frame 5 permitting the branches 8, 8 to be readily inclined inwardly.
- 5 When it is desired to remove the brush from the holder this may be readily done by holding the handle of the brush and pulling outward on first one finger engaging element 13 and then the other whereupon the gripping members 6, 6 may be removed from the edges of the brush.
- 10 By reason of the leg portions 9, 9 of the holder the frame proper will at all times be kept clear of the bottom of the receptacle in which the holder has been placed; and, due to the cross piece 7 of the frame, the user of the holder will have a guide whereby the brush will be placed in the frame well above the lower ends of legs 9, 9.
- 15 From the foregoing it is readily apparent that my present invention provides a convenient and highly useful holder for brushes of the paint brush type whereby the brush may be securely held while immersed, for example in a cleaning fluid or can be temporarily held during inactive periods in a painting operation. Due to the flexible character of the frame and the adjustability of the gripping members the holder is well adapted to effectively retain brushes of varying widths as well as varying thicknesses.
- 20 While the present description sets forth a preferred embodiment of the invention, various changes may be made in the construction without departing from the spirit of the invention, and it is therefore desired that the present embodiment be considered in all respects as illustrative and not restrictive, reference being had to the appended claims rather than to the foregoing description to indicate the scope of the invention.
- 25 40 I claim:
1. A brush holder comprising, in combination, a U-shaped wire frame arranged to be supported in position on the bottom of a receptacle, the vertical branches of the frame being yieldable outwardly, a gripping member located on the free end of each vertical branch and adapted to frictionally engage the bristle base of the brush, whereby the bristles will be disposed within the frame and out of contact therewith.
- 30 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900

vertical branches of the frame, whereby the brush will be held suspended within the frame with the bristles of said brush substantially out of contact with the frame, the free ends of the frame being extended substantially beyond the gripping members and being reversely bent upon themselves to and along the respective gripping members, means securing the respective gripping members to the reversely bent portions as well as the primary portions of the frame, the free ends of the frame which extends beyond the gripping members forming rigid finger engaging elements, whereby upon pulling outwardly upon said finger engaging elements the gripping members will be readily withdrawn from the brush.
